UNITED STATES PATENT OFFICE.

LOUIS ULLMAN, OF NEW YORK, N. Y.

STUFFING BOX, GLAND, AND PACKING THEREFOR.

Application filed January 25, 1923. Serial No. 531,544.

To all whom it may concern:

Be it known that I, LOUIS ULLMAN, citizen of the United States, residing at New York city, in the county of New York and State of New York, have invented certain new and useful Improvements in Stuffing Boxes, Glands, and Packing Therefor, of which the following is a specification.

My invention relates to stuffing boxes, glands and packing therefor, and is particularly adapted for use in door closing devices of the type which combines a powerful spring for closing the door and a piston moving in a cylinder against a liquid to check or control the closing action of the spring.

The primary object of the invention is to improve the construction of such devices and to reduce to a minimum any possible leakage of the liquid through the stuffing box.

In stuffing boxes used for this general work, it has been found that within a relatively short period of time and under normal conditions the packing surrounding the operating shaft becomes loosened and small quantities of liquid are permitted to escape into the spring chamber. The result of such leakage will cause dripping of the liquid from the device and will ultimately impair the checking action of the device.

It is believed, however, that the rapid deterioration of the packing is not alone due to any particular means used to hold the packing in the stuffing box, but to the general design of the latter, which does not provide supporting means for the crank end of the operating shaft. As a result, the tremendous pressure exerted against the lower portion of this shaft by the combined energy of the spring and resistance of the confined liquid, sometimes reaching a maximum pressure of two hundred and fifty pounds to the square inch, tends to offset the alignment of the shaft with a consequent loosening of the surrounding packing. Therefore, it is a further object of the present invention to provide a suitable supporting bearing for the operating shaft between the packing and the crank arm, the said bearing being formed by a substantially integral part of the stuffing box.

The invention is illustratively exemplified in the accompanying drawings, in which—

Figure 1 is a side elevational view of a door closing device with parts shown in sec-

tion, the operating shaft, and the stuffing box for supporting the said shaft above and below the packing.

Figure 2 is a substantially sectional view of a slightly modified form of the operating shaft, stuffing box, gland and packing.

Referring to the drawing and particularly to Figure 1, 10 designates the casing of the door check and closer, and 11 the spindle or operating shaft projecting vertically and axially thereof to which the usual lever arm (not shown) is secured. The interior of the casing 10 is divided into two compartments 12 and 13, the former located in the upper portion of the casing and adapted to contain the coiled operating spring 14, and the latter compartment is cylindrically shaped and the axis of which is substantially at right angles to the axis of the other compartment 12. This cylindrical chamber 13 is adapted to contain liquid against which a piston 15, moving in the cylinder, is operated by rotary movement of the shaft 11. The piston 15 is operated by the lower end of the shaft 11 through a connecting rod 16 and crank arm 17, the latter being rigidly secured to the extreme lower end of the shaft.

The partition 18 between the upper and lower chambers 12 and 13 is provided with a threaded opening 19 through which a stuffing box 20 is projected. The stuffing box 20 is axially aligned with the operating shaft 11 and provides two lower bearings for the latter adjacent its lower end. The stuffing box itself comprises a casing 21 having an enlarged hexagon head 22, reduced central portion cylindrically shaped and exteriorly threaded to be received by the threaded opening 19, and a still further reduced cylindrical lower portion having a bore 23 to bear about the lower end of the shaft 11. The head 22 is provided with an annular channel 24 projecting from the face of the head well into the interior thereof. The outer wall of this channel 24 is threaded and the inner wall 25 is a narrow upright annular piece having its inside or inner wall threaded. Projected inwardly from the base of the wall 25 and on a plane slightly above the bottom of the channel 24 is a grooved packing seat 26. The diameter of the inner periphery of this seat 26 is substantially greater than the diameter of the operating shaft 11 projecting axially therethrough, so as to allow considerable space

110

between the two members to accommodate the packing, hereinafter described. From the inner periphery of the seat 26 the interior wall of the casing 21 bevels outwardly and then vertically through the central portion to a shoulder 27, and thereafter dropping vertically to a second shoulder 27^a which is provided with a continuous groove in its surface and the inner diameter of which is the bore 23 in the lower cylindrical portion of the casing.

The packing and glands carried by the stuffing box 20 and mounted in the interior of the latter are above a coiled wire spring 28 having its lower end seated in the groove of the second shoulder 27^a and the opposite end yieldably engaging with an adjustable portion of the packing. The packing proper consists of an inner conically shaped member 29, having a through bore 30 to receive the shaft 11 and a partially threaded lower portion to screw over the threads 11^a of the shaft itself. The upper face of the member 29, when in operative position, is raised considerably above the packing seat 26, so as to present an inclined surface adjacent the inner periphery of the seat. A second member of the packing is a conically shaped leather washer 31 having an outwardly projecting portion adapted to overlie the seat 26. The inclined portion of this washer 31 rests against the corresponding portion of the member 29 and is held tightly in position by the spring supported conical sleeve 32 which bears against the outside surface of the washer. Screwed into the threads of the inner wall 25 and brought to bear tightly against the projecting portion of the washer 31 overlying the seat 26 is a packing nut 33 comprising an exteriorly threaded ring provided with slots in its upper surface to receive the nibs of a spanner. The portion of the shaft 11 immediately above the packing is further supported in a bearing 34 which consists of a hub 35 having a bore to receive the shaft and an outwardly projecting annular portion terminating in a downwardly disposed flange 36, exteriorly threaded and adapted to be received by the threaded outer wall of the channel 24. In order to insure perfect movement of the shaft 11 and crank arm 17 the latter is separated from the lower edge of the bearing or bore 23 by a bushing or washer 37.

In the form of the invention shown in Figure 2, the stuffing box casing 21^a is similar to that of Figure 1, except that the axial opening in the head portion 22^a is not provided with a channel, but simply forms a shoulder or seat 26^a. The inner periphery of this seat 26^a defines the upper edge of a packing chamber 40 the wall of which is slightly inclined inwardly and terminates in a grooved shoulder 27^a adjacent the lower end of the casing 21^a. The wall of the open-

ing in the head portion 22^a is threaded and the surface of the shoulder or seat 26^a is grooved.

Mounted to operate in the opening through the casing 21^a is the spindle or shaft 11 having a threaded band 11^a adapted to receive the threaded hub 41 of a packing gland 42. The annular flange of the gland 42 is provided with a grooved under surface 43. Supported in the groove of the shoulder 27^a is the lower end of the coiled spring 28, while the upper end of the latter engages with a packing sleeve 44 to yieldably support the sleeve about the smooth outer wall of threaded hub 41. The upper portion of the sleeve 44 projects outwardly to provide an annular surface having a periphery which will loosely fit the opening through the seat 26^a. The packing comprises an annular washer 45 composed of leather and of a size which will fit between the threaded inner of the wall of the casing 21^a and the outer surface of the hub 41. In the described position it will be noted that the washer 45 is normally being held against the under side of the packing gland 42 and the projecting marginal portion beyond the gland rests on the seat 26^a. In order to firmly fix the position of the washer 45 against possible movement the latter is compressed between the seat 26^a and the under face of a packing nut 33^a in the form of a ring threaded to fit the threads on the inner wall of the opening in the casing 21^a. This ring or nut 33^a is adapted to be screwed into the space between the periphery of the gland 42 and the opposite wall of the opening. A bearing cap 36^a is introduced into the threaded opening in the head 21^a and is moved against the packing nut and gland, the central portion of the cap being provided with a bearing hub 35^a to support the portion of the shaft 11 immediately above the packing.

In operation the movable members of the stuffing boxes function in substantially the same manner, i. e., rotary movement of the spindles or shafts 11 will carry the packing glands 29 or 42 in a similar rotary movement, and the springs 28 will both exert an upward and yieldable pressure against the packing sleeves 32 and 44. In Figure 1, the packing 31 is held tightly against the movable gland 32 so that any liquid having found its way into the lower portion of the casing 21 will be unable to force its way past the conical washer and into the spring chamber 12. It is particularly pointed out that as the washer 31 is gradually worn down by the rotary movement of the gland 29 the spring supported sleeve 32 will be forced upwardly against the washer to cause the latter to more closely embrace the surface of the gland and in this way a constant liquid tight fit may be provided.

In Figure 2, the rotary movement of the shaft 11 and gland 42 will cause the latter to move relatively to the packing or washer 45 and spring supported sleeve 44 in which case it will be noted that as the washer wears away the sleeve 44 will be forced upwardly against the inner marginal portion of the fixed washer 45 by the action of the spring 28.

10 It has been found that the life of the packing or washer may be greatly lengthened by gripping a marginal portion of the latter between the surfaces of the seat 26 and packing nut 33 and allowing the inner portion to remain free. In the present invention the upper surface of this inner marginal portion of the packing rests against the under surface of the gland and the opposite surface of the packing is yieldably engaged by the slideable sleeve, all of which gives a substantially flexible liquid tight connection between the shaft and the stuffing box. Leakage under this construction is practically overcome and the efficiency of 25 the checking device is not impaired by loss of liquid from the piston chamber.

Having described my invention, what I desire to claim and secure by Letters Patent is:—

30 1. A stuffing box for a movable shaft, comprising a casing provided with a stepped opening, a compressible packing ring marginally engaged with a step in said opening, a member movable with said shaft and relatively to the packing ring, and a yieldably supported sleeve disposed about the inner marginal portion of said packing ring, whereby the latter may be held in contact with the member.

40 2. In a stuffing box for the purpose described, the combination with a movable shaft having a projecting member, of a casing surrounding said shaft and provided with a bearing at one end, a packing washer 45 having its marginal periphery rigidly secured to said casing and its inner portion overlying said member, a sleeve mounted around a portion of said washer and yieldably supported against the latter to hold it 50 constantly in engagement with the member.

3. In a stuffing box for a movable shaft,

the combination with a casing having a stepped opening, a flexible packing ring marginally supported on a step in the opening, a packing nut movable against the ring to rigidly secure the latter to the casing, a conically shaped member movable with the shaft and relatively to the unattached inner portion of the packing ring, a conically shaped sleeve disposed about the packing ring to hold the latter in engagement with the surface of the member, and means for yieldably supporting the said sleeve axially of the shaft.

4. In a stuffing box of the character described, the combination of a marginally engaged packing ring, a movable member having a projecting flange overlying the unattached portion of the packing ring and a hub portion extending through the opening 70 in the ring, and a sleeve slidably mounted on said hub and provided with a projecting flange adapted to underlie the unattached portion of the ring.

5. In a stuffing box of the character described, the combination with a casing having an opening therein to receive a shaft, said opening being arranged in sections with a grooved shoulder therebetween, of a packing ring marginally held against the 80 grooved shoulder and projecting inwardly into the lower section of the casing, a member carried by the shaft and projecting through the opening in the central unattached portion of the ring, a sleeve having 85 an upper diameter equal to the inner periphery of the said shoulder and adapted to be yieldably supported over the projecting portion of the packing ring to move axially thereof, said sleeve being adapted to constantly hold the ring against the surface of the movable member, and bearings for the shaft adjacent opposite ends of packing members, one of said bearing being an integral part of the lower portion of the casing and the other of said bearing being an 95 insertable cap carried by the casing and surrounding the shaft adjacent the upper surface of the said packing member.

In testimony whereof I affix my signature.

LOUIS ULLMAN.
